UNITED STATES PATENT OFFICE

OTTO WALLSCHLAEGER, OF MILWAUKEE, WISCONSIN.

FASTENING FOR THRESHING-MACHINE TEETH.

No. 923,221.

Specification of Letters Patent.

Patented June 1, 1909.

Application filed July 6, 1908. Serial No. 442,025.

To all whom it may concern:

Be it known that I, OTTO WALLSCHLAEGER, of Milwaukee, Wisconsin, have invented a Fastening for Threshing-Machine Teeth, of which the following is a specification.

My invention relates to an improved mode of fastening the insertible teeth for the cylinders and concaves of threshing-machines.

Up to the present time great difficulty has been experienced in finding a means for fastening thresher-teeth in position so securely as to prevent them from working loose during operation and yet of such character that they may be easily removed and replaced. The general means in use has been screws or screw-threaded devices. These are open to serious objections that they frequently work loose even when furnished with lock-nuts, elastic washers and the like, and that in the case of the cylinder being on the inner faces of the cylinder bars, they are difficult to get at with a wrench and to screw up tight in place; and this is especially true when the teeth are set close together.

In my invention I aim to provide a fastening device which shall entirely dispense with the use of screws and screw-threads and which moreover shall have the characteristic that any looseness or wobbling of the teeth shall have the effect of drawing them tighter in place rather than allowing them to become looser. And I further aim to provide a fastening with the additional characteristic that it can be set up and the teeth secured or removed in a few moments and without the use of a wrench, tool, or special difficulty of any kind.

I also aim to produce a device which can be manufactured and added to the machine at an expense not greater than that of constructing fastenings of the ordinary kinds heretofore in use.

My invention consists in general in providing a wedge adapted to engage with a notch or slot on the shank of the tooth, combined with a spring acting to press or pull the wedge up into place. In combination with these features, where an open notch is used, I also use a special form of washer adapted to hold the wedge in place.

My invention consists further in the special constructions and combinations which will be hereinafter described and particularly set forth in my claims.

In the accompanying drawings I have

shown the most improved form of my invention in connection with portions of a cylinder and concave of a threshing-machine, and herein—

Figure 1 represents in transverse section a part of a cylinder and concave, the teeth of which are provided with my improved fastening; Fig. 2 is a longitudinal section through one of the bars carrying the teeth, showing the tooth and wedge in elevation; Fig. 3 is a perspective of the washer, and Fig. 4 is a perspective of the wedge.

In these drawings every reference letter refers always to the same part.

Fig. 1 shows a common form of threshing-cylinder *a* carrying bars *b* in which are set rows of teeth *c*, and a portion of a concave *d* having bars *e* also carrying rows of teeth *c*. These elements may be of any pattern, style and shape, the latter forming no part of my invention.

The shanks *f* of the teeth *c* are provided with tapered shoulders *g*, said shanks fitting in sockets *h* in the bars *b* and *e* which are preferably flared at the ends as at *i*, to fit the shoulders *g*. The ends of the shanks *f* project beyond the back side of the bars *b* and *e*, and each shank is provided with a recess *j* in which engages a wedge *k*. The recess *j* may consistently with my invention be in the form of a slot anywhere in the bar, but I prefer to make it in the form of an open-sided notch in one side thereof, as such a notch can be forged directly in the tooth instead of being cut out specially. In the case of such an open-sided notch or slot, I use a washer *m* having a central aperture *n* formed by turning up the metal to form a tongue or abutment *o* thereof at right angles to the plan of the washer, said abutment lying against the open face of the notch or slot *j* and holding the wedge *k* against lateral displacement.

The wedge *k* is held in place by means of a spring *p* which is connected with the small end of the wedge by a hole *q* therein, or a hook *r* as shown in the case of the lower teeth, Fig. 1; said spring *p* being connected to the wedges of two adjacent teeth which are turned in opposite directions as shown, so that the effect of the spring is to draw the two wedges together, and to draw each wedge more tightly into place. Ordinarily the rows of teeth in the cylinder and concave are even in number, so that there will be a whole number of pairs of teeth to be united by the

springs *p*; but in case of an uneven number of rows, I may fasten the springs *p* of the odd teeth to a fixed bar or like object *s*.

While I prefer to use the spring *p* as shown 5 to connect the two wedges it is not necessary that this form of spring or any form of spring be used as a simple wire or any form of connection holding the two wedges together would serve the purpose consistently with 10 my invention, though less perfectly.

While I have hereinabove shown the most improved form of my invention, I wish it understood that not all of the features are essential thereto or necessarily made in the exact form shown, but various changes and modifications in the constructions as herein shown may be made without departing from the spirit of my invention, and I wish it understood therefore that the latter is not otherwise limited than by the reasonable scope of my claims.

Having thus described my invention, what claim as new and desire to secure by Letters Patent is:

25. 1. A fastening for thresher-teeth comprising, in combination with a tooth having a recess in the shank thereof, a wedge fitting in said recess and holding the tooth against pulling out, and resilient means for pressing said wedge more firmly into place.
2. A fastening for thresher-teeth comprising, in combination with a tooth having a recess in the shank thereof, a wedge fitting in said recess and holding the teeth against pulling out, and a spring acting to draw said wedge more firmly into place.
3. In a threshing-machine, a fastening for the teeth thereof comprising, in combination with two adjacent teeth each having a transverse recess in the shank thereof, two transverse wedges fitting in the respective recesses, and a spring connecting the two wedges.
4. In a threshing-machine, a fastening for the teeth thereof comprising, in combination with two adjacent teeth each having a transverse recess in the shank thereof, two transverse wedges fitting in the respective recesses, and having their small ends toward each other, and a connection between small ends of the two wedges tending to draw them together in a direction lying across said recesses.
5. In a threshing-machine, a fastening for

the teeth thereof comprising, in combination with two adjacent teeth each having a transverse recess in the shank thereof, two transverse wedges fitting in the respective recesses, and a tension-spring connecting the small ends of the two wedges.

6. In a threshing-machine, means for fastening the teeth thereof comprising, in combination with a tooth having an open-sided recess in one side of the shank thereof, a transverse wedge set in said recess and slideable parallel to the face of said recess to draw up the tooth, means for preventing said wedge from retracting, and an abutment facing the open side of said recess and holding said wedge against lateral displacement.

7. In a threshing-machine, means for fastening the teeth thereof comprising, in combination with a tooth having an open-sided recess in one side of the shank thereof, a transverse wedge set in said recess, means for preventing said wedge from retracting, and a washer having an aperture through which said shank passes and an upright tongue at one side of said aperture forming an abutment lying against the open face of said recess.

8. In a threshing-machine, means for fastening the teeth thereof comprising, in combination with a tooth having an open-sided recess in one side of the shank thereof, a washer through which said shank passes provided with an upright tongue subtending the open side of said recess, a transverse wedge fitting in said recess, and a spring acting on said wedge to press it more tightly into place.

9. In a threshing-machine, fastening means for the teeth thereof comprising, in combination, a pair of adjacent teeth each having an open-sided recess in one side of the shank thereof and a washer through which said shank passes having an upright abutment subtending the open face of said recess, a pair of transverse wedges fitting in the respective recesses in opposite directions, and a spring connecting the small ends of the two wedges.

In witness whereof, I have hereunto set my hand this third day of July, 1908.

OTTO WALLSCHLAEGER.
